A. K. SIMMONS

DRAFT RIGGING

Filed Jan. 10, 1925

UNITED STATES PATENT OFFICE.

ALBA K. SIMMONS, OF ROANOKE, VIRGINIA, ASSIGNOR TO THE SYMINGTON COMPANY, OF BALTIMORE, MARYLAND, A CORPORATION OF MARYLAND.

DRAFT RIGGING.

Application filed January 10, 1925. Serial No. 1,657.

The invention relates to draft rigging for railway cars and has particular reference to means for connecting the coupler shank with the yoke.

5 The principal object of the invention, generally stated, is to provide means for pivotally connecting a coupler and yoke, said means comprising an upright pin or key, the coupler and yoke being provided with 10 slots so disposed and arranged that accidental disengagement of the coupler connecting means while the parts are in service is impossible.

The object of the invention, more specifically stated, is the provision of a draft rigging having a yoke provided in its arms with elongated slots adapted to register with similar slots in the coupler shank to permit the insertion of a pin or key designed 20 to be subsequently rotated to bring retaining gibs thereon into engagement with the arms of the yoke, the slot arrangement being such that the expansion of the draft gear or cushion device will hold the coupler shank in 25 such relation to the yoke that portions of the slots will be out of registration, the opposite ends of the respective slots engaging against the pin or key.

Another object of the invention is to provide a structure of this character in which means is provided engaging one end of the pin or key for preventing rotation thereof out of its normal position so that the gibs cannot accidentally come into registration 35 with the slots.

A further object of the invention is to provide a draft rigging in which the coupler shank and yoke are slotted for the accommodation of a pin or key which provides 40 the pivotal connection, the combined lengths of the yoke slots and coupler shank slot being such as to permit the necessary and proper relative movement of the coupler with respect to the yoke, the provision of the slot in 45 the coupler shank making it possible to have short slots in the yoke arms so that the yoke arms may be made comparatively narrow at points spaced somewhat back from the ends, thus permitting the utilization of front stops 50 for the draft gear of greater inward projection than is ordinarily possible, the increase in the inward extension being of material advantage in providing increased bearing surfaces for the draft gear, or following thereof, and consequently reducing

likelihood of breakage or distortion at this point.

Another object of the invention is to provide a pin or key for connecting the coupler shank and yoke of such construction 60 that in case of breakage it may be replaced at small expense inasmuch as it will be unnecessary to discard the coupler, as is the case with certain types of connections.

In the drawings:

Figure 1 is a view partly in plan and partly in horizontal section illustrating the invention.

Figure 2 is a view made partly in section along the line 2—2 of Figure 1, certain parts 70 being in elevation.

Figure 3 is a cross section on the line 3—3 of Figure 2.

Fig. 4 is a bottom plan view of the draft 75 key.

Referring more particularly to the drawings, I have illustrated a portion of a draft rigging including center sills 1 carrying the end sill 2 beyond which is the striking casting 3. Suitably secured between the center sills is the backstop 4 against which engages the rear end of a yoke 5 here shown as vertically arranged, within which is located any suitable or preferred draft gear or cushion device, indicated at 6, cooperating with front stops 7 secured to the center sills. In the present instance I have shown a yoke filler 8 within the inner or rear end of the yoke and fitting between it and the draft gear, the filler having means, such as the extensions 9, for preventing it from dropping down out of place. The forward ends of the arms of the yoke are formed with elongated slots 10.

The numeral 11 designates the coupler shank which engages against the forward end of the draft gear 6 and which is formed with an elongated slot 12 which may be of the same size and shape as the slots 10 in the yoke arms and adapted to register therewith to permit insertion of the connecting means, which in the present instance, I have shown as a vertical pin or key 14. This key or pin is represented as of cylindrical formation and provided at its ends with retaining means herein disclosed as consisting of gibs 15 capable of passing through the registering slots 10 and 12 when the pin or key is properly turned, but ordinarily adapted to engage against the upper and lower surfaces 105 110

of the upper and lower yoke arms, respectively, for preventing longitudinal movement of the key when in place.

It is desirable that means be provided for positively preventing rotation of the key or pin while the car is in service and this feature may conveniently be carried out by providing a carry iron 16 secured beneath the center sills in such position as to extend 10 across the lower end of pin or key, the carry iron having guide means such as a groove or way 17 therein slidably receiving an extension 19 of angular shape on the lower end of the key or pin.

15 Assembling of the parts can be effected only when the draft rigging is out of the car as this is the only time when the slots 10 and 12 can be brought into registration. The key or pin is inserted while in such 20 position that the gibbs thereon may pass through the slots, after which the key is given a quarter turn to bring the gibbs in transverse relation to the slots. The draft gear or cushioning unit is then inserted and 25 the parts raised to proper assembled position between the car sills. When the carry iron is applied so that the pin engages therewith, the co-action of the extension 19 with the groove or way will prevent subsequent 30 rotation of the key or pin. When in normal position the cushioning unit will maintain the major portion of the slots 10 and 12 out of registration, the outer ends of the slots 10 and the inner end of the slot 12 engaging 35 35 against the pin or key so that even though no means were provided for preventing rotation thereof the key would still be prevented from displacement as the gibbs would engage the yoke arms at one end of the slots 40 therein. In service, it is evident that the movement of the pin with respect to the car underframe is permitted as the groove or way 17 in the carry iron is elongated.

45 It will be observed that by providing a slot in the coupler shank instead of having the yoke alone formed with slots to permit the necessary relative movement of the coupler and yoke, the length of the yoke slots may be greatly reduced, thereby making it 50 possible to form the yoke comparatively narrow at a point somewhat back from the forward end instead of wide as would be necessary to give proper strength at the sides of long slots. This feature of comparative 55 narrowness of the yoke is of great importance inasmuch as it then becomes possible to utilize front stops for the draft gear, or front follower thereof, which may extend further into the space between the center 60 sills and thus provide an increased bearing surface for the follower or draft gear which will reduce likelihood of distortion or breakage at this point. Another distinct feature of advantage is that in case of breakage of 65 the draft connection only the pin or key

itself need be discarded and replaced by a new one, the expense being slight as compared with the replacement of a coupler.

While I have shown and described a preferred embodiment of the invention, it 70 should be understood that the right is reserved to make all such changes in the form, construction and arrangement of parts as will widen the field of utility and increase 75 the adaptability of the device, provided such variations and modifications constitute no departure from the salient features of the invention or the scope of the hereunto appended claims.

Having now described my invention, what 80 I claim as new and desire to secure by Letters Patent, is:

1. In a draft rigging, the combination of a vertical yoke enclosing a draft gear and having its arms provided with elongated 85 slots, a coupler shank extending between the arms of the yoke and formed with an elongated slot adapted to register with the first named slots upon compression of the draft gear, means for pivotally connecting said coupler and yoke comprising an upright key formed with gibbs on its ends adapted to pass through the slots when in one position and too long to pass through said slots when rotated from said position, and means, 90 independent of the yoke, for holding said key in a position to prevent movement thereof in the direction of its length.

2. In a draft rigging, the combination of a vertical yoke enclosing a draft gear and having its arms provided with elongated slots, a coupler shank extending between the arms of the yoke and formed with an elongated slot adapted to register with the first 100 named slots upon compression of the draft gear, means for pivotally connecting said coupler and yoke comprising an upright key, means for preventing movement of said key in the direction of its length, and means for preventing rotation of the key.

3. In a draft rigging, the combination of a vertical yoke enclosing a draft gear and having its arms provided with elongated slots, a coupler shank extending between the arms of the yoke and formed with an elongated slot adapted to register with the first 105 named slots upon compression of the draft gear, means for pivotally connecting said coupler and yoke comprising an upright key, said key having projections thereon adapted normally to extend transversely with respect to the slots and means for retaining said projections in normal position.

4. In a draft rigging, the combination of a vertical yoke enclosing a draft gear and having its arms provided with elongated slots, a coupler shank extending between the arms of the yoke and formed with an elongated slot adapted to register with the first 115 named slots upon compression of the draft gear, means for pivotally connecting said coupler and yoke comprising an upright key, said key having projections thereon 120 adapted normally to extend transversely with respect to the slots and means for retaining said projections in normal position.

125

130

gear, a draft pin detachably engaged through said slots for pivotally connecting said coupler and yoke, means on the key normally extending transversely of the slots 5 and engaging the yoke for preventing movement of the pin in the direction of its length, and supporting means for the yoke provided with a portion cooperating with the lower end of the key to prevent rotation 10 thereof during normal operation.

5. In a draft rigging, the combination of a vertical yoke enclosing a draft gear and having its arms provided with elongated slots, a coupler shank extending between the 15 arms of the yoke and formed with an elongated slot adapted to register with the first named slots upon compression of the draft gear, a draft pin detachably engaged through said slots for pivotally connecting said coupler and yoke, a carry iron located beneath the pin, and co-acting means on the pin and the carry iron for preventing rotation of the 20 pin.

6. In a draft rigging, the combination of 25 a vertical yoke enclosing a draft gear and having its arms provided with elongated slots, a coupler shank extending between the

arms of the yoke and formed with an elongated slot adapted to register with the first named slots upon the compression of the 30 draft gear, a draft key detachably engaged through said slots for pivotally connecting said coupler and yoke, and a carry iron located beneath the key and having a guide, the key having an extension slidably and 35 non-rotatably engaged within the guide.

7. In a draft rigging, the combination of a yoke operatively connected with a draft gear and having its arms provided with elongated slots, a coupler shank extending between the arms of the yoke and formed with a slot, a draft key engaged through said slots and serving as a pivotal connection and means locking said key in position during normal operation, the provision of the 40 slot in the shank making it possible to reduce the length of the slot in the yoke and correspondingly reduce the width of the yoke 45 at a point back from the forward end thereof and providing more space at the sides of 50 the yoke for the location of stop members for the draft gear.

In testimony whereof I affix my signature.
ALBA K. SIMMONS.
